DESCRIPTION

U.S. PATENT DOCUMENTS

FIG. 1 is a front, top, right perspective view of the radiused
insert of the new design;

FIG. 2 is a top plan view thereof;

FIG. 3 is a cross-sectional view along line 3-3 of FIG. 2;
FIG. 4 is a left side view thereof, the right side being a mirror
image;

FIG. 5 is a front side view thereof; and,

FIG. 6 is a bottom plan view thereof.

The broken line showing of environment in the drawings is
for illustrative purposes only and forms no part of the claimed
design.
